GUYON LOCKE, OF BOSTON, MASSACHUSETTS.

VIOLIN-REST.

1,087,066.

Specification of Letters Patent. Patented Feb. 10, 1914.

Application filed May 7, 1913. Serial No. 765,994.

To all whom it may concern:

Be it known that I, GUYON LOCKE, a citizen of the United States, residing at Boston, in the county of Suffolk and State of Massachusetts, have invented new and useful Improvements in Violin-Rests, of which the following is a specification.

This invention relates to improvements in violin rests.

10 The proper position, in which a player should hold a violin, in order to facilitate advanced playing, where the fingers of the player must sometimes for a considerable period make rapid movements on the high 15 notes, with the cords of the wrist and forearm in a constrained position as, for example, in playing the upper notes on the G string, is a position difficult for beginners to learn, and is acquired only by much practice 20 and with the aid of persistent correction by a teacher.

It is an object of the invention to accomplish the important result, never before attained, so far as I am aware, of providing 25 means with the aid of which a person, whether a beginner or otherwise, puts a violin automatically into proper position and automatically holds it in such proper position while playing.

30 It is another object of the invention to provide an improved construction of pad and of detachable fastening combined therewith, and to provide the other features of novelty and utility which are incidental to 35 the structure hereinafter described. And it is the intent of the patent to cover in the claims such features of novelty as reside in the structure disclosed.

In the accompanying drawings, which represent 40 an embodiment of the invention, Figure 1 is an elevation of a violin with the rest attached, viewed from a position beside the head end; Fig. 2 is a plan, at the level of Fig. 1, looking down upon the rest; Fig. 45 3 is an elevation in section on the line 3—3 of Fig. 2; and Fig. 4 is a fragmentary elevation in section on the line 4—4 of Fig. 3.

The drawing, in Fig. 1, shows the violin and its rest in position thereon somewhat as 50 it would be seen if viewed from a point straight outside a player's left shoulder, such point being slightly to the rear of the head end of the violin, except that the drawing shows the violin and its rest as tipped 55 up into a horizontal plane, whereas for the true playing position one must imagine Fig.

1 to be tipped somewhat backward and downward to the left. The body of the violin is marked 10; 11 signifies the rest with which the invention is concerned; 12 ⁶⁰ the base plate holding it on the violin; and 13 the clamp by which the chin rest 14 and said base plate 12 are held in place. The chin rest and its clamp may be of any ordinary or suitable construction. The plate 12 ⁶⁵ is held between the body of the violin and the bottom loop-claw of the clamp 13, this plate having a depending terminal tongue 12' which engages behind the terminal bar 13' of the clamp and thus prevents the plate ⁷⁰ from being pulled out.

In Fig. 2, which is a plan, the position the violin's edge would occupy, if present, is indicated by the dotted line 10, although the violin is assumed to be removed in order that ⁷⁵ the eye may see the top of the plate 12 and of the pad 11 and their position relative to the violin. The plate 12 runs under the violin and rather close to the body thereof obliquely toward a line under the main longitudinal axis of the instrument; and the rest 11 attached thereto is at a little distance ⁸⁰ forward from the violin edge and is alined in a plane approximately perpendicular to the plane through the main longitudinal ⁸⁵ axis of the violin. This rest is so adapted by its position and characteristic short concave pad shape illustrated in Fig. 1, that there is only one place where it can be comfortably applied by the player to his person. ⁹⁰

In this position the pad edge which is seen at the left in Fig. 2 and is toward the eye in Fig. 1, is pressing outward against the acromion process, or the body of muscles and tissues surrounding that bone; with the ⁹⁵ concavity of the pad following this mound forward and downward a short distance. It is positioned properly as respects elevation, or degree of tipping forward, by the upper edge of the muscle (pectoralis major) that ¹⁰⁰ is inserted in the upper end of the humerus. When a player essays to hold a violin so equipped in position for playing, the pad seeks the position described automatically, as it were, *i. e.*, if the player does not put it ¹⁰⁵ there, the player finds himself shifting position from one place to another until he finally gets it there. The short and abruptly concave curved form of the pad brings the lower end thereof at such an angle ¹¹⁰ that the player cannot comfortably rest it down too low, nor on his chest in any way,

nor tip it. When the player presses downward on the chin rest, the rest 11 being in proper position, the violin is gripped between his chin and shoulder in the position 5 described, and this is precisely the approved position in which a violin should be held to give utmost freedom and endurance to the fingers and to the cords of the fore-arm as above mentioned. This pressure of the chin 10 holds the violin fixedly in said position. Hence, the player instead of as heretofore having tediously to learn to put the violin into proper position and then to maintain it there, has only the simple or negative task 15 of refraining from removing it; and this is really no task because any tendency to draw it away will be corrected by the effect of the rest itself. In this manner a learner can acquire a habit of proper position; after 20 which he may use the rest or not at will.

Heretofore it has been customary for players to wear a pad under the clothing to relieve pressure or prevent pain resulting from holding an instrument, these pads having 25 no connection with the violin, and being merely worn on the person or placed thereon temporarily; and it has also been proposed to attach a pad or spring arch to a violin for a similar purpose; but the present invention 30 while incidentally providing a cushion as do those prior devices, also provides an appliance so related to the form of the human anatomy and so related to the form of a violin, that there is but a single position 35 which the appliance can occupy on the player's body and but a single position which it can occupy on the violin. As a result, when the violin carrying the appliance is held so that that appliance occupies its 40 said sole position on the player's body, there is only one position in which the violin can be at that moment. The sole position of the pad 11 is therefore so located in advance by the manufacturer of the appliance that the 45 corresponding position of the violin is that position which is the proper or approved position for playing. I have found by experience that the position illustrated is substantially correct for any person of adult or 50 adolescent age.

So far as my experience goes this statement of universal adaptability is true, but if more extended experience shall show that it is too broad, modification of the structure 55 to suit any particular individual would be easy without departing from the principle of the invention.

The preferred construction of the pad 11 is as follows: A plate 15 of sheet metal is 60 formed into the proper concavity and dimension, and two layers of felt 16, 17 are placed thereunder, substantially duplicating its size and shape. Under them is another layer 65 of felt 18 whose turned up edges inclose the plate 15, the two pads 16, 17, as seen in Fig.

3, being folded over upon the top of plate 15. A covering of velvet or other suitable material 19 surrounds all. The parts folded over on top may then be sewn together, or fastened in any other suitable manner. A cover plate 20 is then placed upon them in the position represented clearly in the drawings, covering and concealing the edges of the felt and velvet, and, with the aid of a single screw 21, furnishing a simple and effective means for binding all parts of the pad together and fastening the whole upon the violin. This is accomplished as follows: A spacing guide 22, fast on the plate 20, projects down through the edge thereof into the under plate 15, where it is inserted in a hole. This insertion, coupled with the holding of its other end by the screw 21 which passes through it, fixes its angular position on the plate 20 and on the pad in general. 75 The screw 21 has a knurled or otherwise rotatable nut 23 which, when turned down tight upon the spacing guide 22, clamps the plates 15 and 20 together with the felt and velvet between them and provides a space, 80 viz., the thickness of the spacing guide 22 in which the forked end of base plate 12 may slide between the nut 23 and the plate 20. The fork on the base plate is made by a terminal slot 12" whose width just fits the 85 width of the spacing guide 22. This fixes the angular position of the pad with respect to the base plate 12 which remains permanently on the violin. Its longitudinal position thereon is fixed by a spring 25 having a hole 90 24 into which the end of screw 21 may enter as a latching pin.

The operation of attaching and detaching is very simple. To attach, the player pushes the guide 22 into the slot 12", until the spring 25 snaps over the pin 21. The angle and position is then definitely fixed. The length of the spacing guide 22 prevents any rotation of the pad with respect to the base plate 12; the arrangement of the forked end of the base plate under the wide nut 23 holds the pad up and the latch keeps the pad from slipping off endwise. The pad is instantaneously removed from this positive lock, in practice, by the player grasping the pad 11 with his thumb under it and his forefinger above it. The latter finger is so applied as to grasp it about where the line from the reference numeral 22 terminates in Fig. 1. The point of the finger, being pressed inward at that place, lifts the spring 25 naturally and easily, so that the pad is unlocked by the mere act of grasping it.

It is obviously important that the plate 20 should be prevented from rotating or shifting its angular position with respect to the plate 15 and spacing guide 22. For clearness in showing this idea mechanically, the spacing guide 22 is represented as being a separate piece, which may be soldered, or other- 125 130

wise fastened on top of plate 20 and which projects into mechanical engagement with the plate 15 that determines the main shape of the pad. It is, however, feasible, and perhaps in practice may be found best, to make the spacing guide 22 by punching or bending upward with a die a portion of the plate 20, omitting the spur connecting this guide directly with plate 15, and fastening the plate 20 to the plate 15 by putting a coating of glue between it and the velvet, thus preventing it from rotating about the screw 21 as a pivot. The screw 21 preferably has a square head or wing lugs 21', or some equivalent contrivance, so that it can be forced into the sheet metal plate 15 and be held against rotation by such lugs. When the velvet is to be replaced, it is only necessary to unscrew the nut 23, and to pry up the plate 20 from the velvet if it be glued thereto, in order to remove the old and put on the new. It will be understood of course that the thickness of the various plates and parts is distorted and in places exaggerated in the drawing for clearness of representation, but the general aspect and shape and size of the pad as drawn show what I have found in practice to be an effective embodiment of the invention.

The position and curvature of the pad 11 is such that when in use it does not press at all upon the player's chest, but makes contact with his body only on the single continuous curved line at the described position, which is practically at the outside line of the torso. While I believe the form and fixed position indicated to be universally adaptable as stated, if later experience shall show any modification necessary to accommodate an individual having an abnormal neck and shoulder combination, that may be done by providing for the pin 21 to be latched at some different distance from the violin edge, without disturbing the angular setting or bearing of the pad 11.

I claim as my invention:—

1. A violin rest comprising a short and abruptly curved concave bearing part hav-

ing a size and curvature adapted to fit the convex curve of the shoulder of a player, 50 above the pectoralis major muscle outside the hollow of the shoulder; and means to fix said bearing part to the violin in a definite predetermined position with respect to the violin body, whereby it predetermines the 55 position of the violin with respect to a player's body.

2. The combination with a violin, of a rest having a concave surface adapted to fit the curvature of a player's shoulder, a base 60 plate fixed on the violin and adapted to be attached to and detached from said rest, a guide fixing the angular position of the rest with respect to said plate; and a latch fixing the longitudinal position of said rest with 65 respect to said plate.

3. In a violin rest, a pad, comprising a concave plate, padding material wrapped around it with edges on the top, and a plate covering said edges and having a guiding 70 and spacing ridge; combined with a screw and nut clamping said parts together, a base plate adapted to be fixed on the violin and having a fork adapted to fit beside the spacing guide under said nut; and means latch- 75 ing the parts together in this position.

4. In a violin rest, the combination of a composite member adapted to rest upon the player, a screw and nut clamping the parts of said members together, the end of the 80 screw projecting above the nut as a pin and there being a spacing guide on said member under the nut; a base plate adapted to be fixed on the violin and having a terminal fork adapted to fit beside the spacing guide 85 under the nut; a flat spring on the base plate, overlying the cleft forming its fork and having a hole adapted to engage with said pin end of the screw as a latch.

Signed by me at Boston, Mass., this 28th 90 day of April, 1913.

GUYON LOCKE.
